UNITED STATES PATENT OFFICE.

JOHN C. WANDS, OF ST. LOUIS, MISSOURI.

FLUID SPEED-GOVERNING CLUTCH.

No. 838,149.

Specification of Letters Patent.

Patented Dec. 11, 1903.

Application filed March 19, 1906. Serial No. 306,822.

To all whom it may concern:

Be it known that I, JOHN C. WANDS, a citizen of the United States, residing at the city of St. Louis, State of Missouri, have invented a certain new and useful Improvement in Fluid Speed-Governing Clutches, of which the following is a full, clear, and exact description, such as will enable others skilled in the art to which it appertains to make and use the same, reference being had to the accompanying drawings, forming part of this specification, in which—

Figure 1 is a longitudinal sectional view through my improved fluid speed-governing clutch. Fig. 2 is a fragmentary end elevational view. Fig. 3 is a cross-sectional view on the line 3 3 of Fig. 1. Fig. 4 is a cross-sectional view on the line 4 4 of Fig. 1. Fig. 5 is a cross-sectional view on the line 5 5 of Fig. 4, and Fig. 6 is a diagrammatic view of the piston cam-groove.

This invention relates to a new and useful improvement in a fluid speed-governing clutch designed to be arranged between driving and driven shafts, so as to control the speed of the latter. The driving-shaft has a piston connected to it in such manner that said piston is capable of reciprocation in a direction longitudinal the driving-shaft, such reciprocation resulting from the rotary movement of said driving-shaft.

The cylinder or casing in which the piston is mounted is connected to the driven shaft, and there are means for regulating the passage of fluid to and from the ends of the casing through by-passes. Thus if the by-passes for the fluid are choked the piston will not move freely in its cylinder and consequently the rotary motion of the driving-shaft will be communicated to the driven shaft. The relative speed of the driven shaft is proportional to the freedom of movement of the piston. When the passage-ways are fully choked, the driven shaft is positively connected with the driving-shaft, and consequently rotates at the same speed as the driving-shaft. When the passage-ways are fully opened, the driven shaft, if it has a load imposed upon it, will remain stationary, while the driving-shaft is rotating at full speed. The partial closure of the passage-ways will impose restrictions upon the liquid displaced by the piston, and, depending upon the degree of restriction, the driving-shaft will drive the driven shaft.

Referring to the drawings, 1 indicates the

driving-shaft, which receives motion from any suitable source of power.

2 is the shaft to be driven. On the end of shaft 1 is mounted a piston 3, provided with a peripheral groove 4. This piston has longitudinally-disposed grooves 5 in its bore, which receive the ends of a cross-pin 6, arranged in the driving-shaft 1. In this manner the piston 3 may move longitudinally the driving-shaft, but is prevented from independent rotation with respect to said shaft. The extreme end of the driving-shaft 1 is preferably provided with a centrally-arranged recess, in which fits a stud 7 on the head-casting 8. This head-casting 8 is provided with a hollow boss on its outer face, in which the driven shaft 2 is pinned. A sleeve 9, surrounding the shaft 1, serves to provide an extended bearing for the head-casting and also to space said head-casting from the hollow casing 10, containing the bypass ways. This casing 10 is connected by suitable screws to the head-casting 8 and at its opposite end is mounted on the driving-shaft 1, there being provided a packing-box around the opening through which the driving-shaft passes.

11 represents pins or projections screwed into the side walls of the casing 10 and held in position by locking-pins 12. The inner ends of these pins 11 enter the peripheral groove 4 of the piston. Casing 10 is provided with hollow walls, as shown, said hollow walls forming by-passes which communicate with the piston-chamber at 10^a at one end of the piston-chamber and at 10^b at the opposite end of said piston-chamber. The openings 10^b coöperate with a rotary valve 13, loosely mounted on the sleeve 9 adjacent the head-casting 8. This valve 13 is provided with a mutilated peripheral flange, so designed that in one position of the valve all of the openings 10^b are closed, and when moved rotatively the openings 10^b may be gradually opened until fully uncovered. The area of the openings 10^a and 10^b exceeds the area of the piston-chamber, and consequently the liquid in the piston-chamber when the openings 10^b stand fully open is free to pass from one side of the piston to the other with little or no impedance.

Valve 13, as shown in Fig. 3, is provided with a rack 13^a upon its hub portion, which rack meshes with a pinion 14, splined to a shaft 15, which passes through a circumferentially-elongated opening of the web of the

- valve 13. This shaft passes through a packing-gland in the head-casting 8 and at its outer end is provided with a sleeve portion 16, having spirally-arranged cam-grooves in its periphery.
- 17 indicates a grooved collar having an extension carrying pins 18, which fit into the spirally-arranged cam-grooves of the part 16. Thus when the sleeve 17 is moved longitudinally rotary motion will be imparted to the shaft 15, and valve 13 will be actuated. The means for moving the sleeve or collar 17 longitudinally consists of a sliding collar 19, connected with the sleeve 17 and coöperating with a yoke-lever 20, fulcrumed on a fixed pivot and carrying a dog 21, designed to engage the notches of a segmental rack 22, whereby the parts may be locked in adjusted positions.
- 20 In operation if the driven shaft 2 is loaded and the openings 10^a fully opened it will be obvious that the rotation of the driving-shaft will cause the piston to reciprocate in its chamber and force the liquid through the openings 10^a and 10^b and the by-passes with which they communicate. If the lever 20 is now moved so as to partially close the openings 10^b, it will be noted that the resistance offered to the flow of liquid through the openings 10^b will be transmitted to the shaft 2, and consequently shaft 2 will be driven, though perhaps at a slow speed. If now the openings 10^b are further restricted, the speed of the driven shaft 2 will be proportionately increased. Should the openings 10^b be fully closed, the incompressible liquid, being incapable of displacement, will hold the piston stationary, and the shaft 2 will be locked to the shaft 1 and the motion of shaft 1 transmitted with its full force and speed to the shaft 2. The gradual opening of the valve and increasing available area of openings 10^b will remove the restrictions upon the flow of the liquid from one end of the piston-chamber to the other and will permit a play of the piston, which results in a corresponding loss of speed in shaft 2, this continuing until the valve is fully opened; when if shaft 2 is carrying a load sufficient to overcome the

friction of the piston in its cylinder the said shaft will be brought to a position of rest, while shaft 1 continues its motion and the piston continues to reciprocate.

Having thus described the invention, what is claimed as new, and desired to be secured by Letters Patent, is—

1. The combination with a driving and a driven shaft, of a piston mounted on the driving-shaft and capable of longitudinal reciprocation longitudinally with respect thereto, a cylinder mounted on the driven shaft in which said piston operates, a by-pass connecting the spaces at the opposite sides of the piston, and means for regulating the flow of liquid through said by-pass; substantially as described.

2. The combination with a driving-shaft, of a piston slidingly mounted on said driving-shaft and capable of longitudinal movement with respect thereto, said piston having a peripheral groove, a driven shaft, a casing connected to said driven shaft and containing a chamber in which said piston operates, a pin on the casing entering the peripheral groove of the piston, and means for controlling the flow of liquid displaced by the piston; substantially as described.

3. The combination with a driving-shaft, of a piston slidingly mounted thereon, said piston being incapable of independent rotation with respect to said driving-shaft, a driven shaft, a casing mounted on the driven shaft and providing a chamber in which said piston operates, pins or projections carried by said casing and coöperating with a cam-groove in said piston, passages in the casing connecting the opposite ends of the piston-chamber, a rotary valve for controlling said passages, and means for imparting motion to said valve; substantially as described.

In testimony whereof I hereunto affix my signature, in the presence of two witnesses, this 14th day of March, 1906.

JOHN C. WANDS.
